UNITED STATES PATENT OFFICE.

CARL AXEL WILHELM HULTMAN, OF STOCKHOLM, SWEDEN.

SEMI-AUTOMATIC TELEPHONE-EXCHANGE.

1,256,322.

Specification of Letters Patent. Patented Feb. 12, 1918.

Application filed March 18, 1916. Serial No. 85,119.

To all whom it may concern:

Be it known that I, CARL AXEL WILHELM HULTMAN, telephone manager, a subject of the King of Sweden, residing at Stockholm, Sweden, have invented certain new and useful Improvements in Semi-Automatic Telephone-Exchanges, of which the following is a specification.

The invention relates to semi-automatic telephone exchange systems in which a number of junctions to which the calling subscribers' lines are connected by means of call finders pre-selectors or the like, is assigned to each operator's position and in which the connections are established by means of automatic switches under the control of register or call storing devices which, after having been set by the operator according to the member wanted, govern the selective movement of the switches. In semi-automatic systems of this class hitherto known the register devices of each position were usually all arranged in common to all junctions of the corresponding position and, upon a call, an idle one was automatically connected to the calling junction. This arrangement, evidently, requires special switches and circuits for selecting an idle register device and connecting the same to the calling junction.

One object of the present invention is to simplify said circuits and switching means so as to obtain reliable operation and a quick connection of the register with the junction. To that effect the junctions at an operator's position are divided into a number of sub-groups each having a register device particularly associated with it. In this arrangement there is, evidently, no selection of idle register devices and the means for connecting up the registers can be made considerably simpler and may consist only of relays in which case the connections are effected instantaneously.

Other features of the invention relate to means for allowing only a certain maximum number of unattended calls to be received simultaneously at an operator's position, or in a group of junctions in a system of the kind just described. In case of a maximum number of one call for instance, all junctions of the positions or groups in question are made inaccessible for further calls when

a call is made on one of the junctions the sub-group including the calling junction remaining inaccessible until the connection has been completed while the other sub-group or sub-groups of the position or main group are made available for another call as soon as the call has been attended to by the operator.

In case two or more simultaneous calls are allowed as a maximum the arrangement is such that all junctions of a sub-group are made inaccessible when a call is made on one of them all junctions assigned to the operator's position being made inaccessible when the maximum number of calls is attained, while, as soon as one call has been attended to by the operator, the junctions of one or more non-engaged sub-groups are made available for another call. In this case a simple circuit arrangement may be obtained by dividing the junctions allotted to an operator's position into a number of main groups or sections each comprising a number of sub-groups and adapted for a maximum number of only one unattended call the number of such selections corresponding to the maximum number of simultaneous calls allotted to each section working independent of the other in the manner above described.

It has been found practical to divide all junctions of an operator's position into two sections corresponding to a maximum number of two simultaneous unattended calls each section comprising two sub-groups and the corresponding register devices. The key-board is preferably arranged in common to all register devices of the position but, if required, two key-boards may be provided for each section. When a call is coming in on one junction all junctions of the corresponding section are made inaccessible for further calls and the calling junction is connected to the operator's telephone. After having received the number wanted the operator writes it down on the key-board and operates a starting button whereby the key-board is connected to the register device of the sub-group in question which is set according to the number wanted the key-board being immediately after disconnected from the register and made available for another call. At the same time, the con-

necting operation is started under the control of the register and all junctions of the section in question except those of the engaged sub-group are made available to receive another call. While the connecting operation is going on a second call may come in on a junction of the other sub-group of the same section or on a junction of the other section which call is attended to in the same way as just described. In the last instance at first all junctions of the section are made inaccessible but as soon as the starting button is pressed down the junctions of the non-engaged sub-group are made available for another call. Two calls may come in simultaneously, one in each section, but only one can be connected at each time to the operator's telephone.

The invention is illustrated in the accompanying drawings in connection with a telephone exchange system according to the British specification No. 13,362 of 1914, in which the connections are established by means of large connector switches having a capacity of 10,000 lines. The movable contacts of such switches are preferably arranged to be set to both sides in two principal directions, the subscriber's line wires being arranged in four groups with the movable contact carrier in a central position with regard to said groups, as described in British specification No. 4,285 of 1915.

Figure 1 shows the arrangement at the operator's position.

Fig. 2 is a circuit diagram of the register or call storing device and the group selector.

Fig. 3 is a circuit diagram of the connector.

The figures illustrate only the numerical selection as the non-numerical selecting operation or the pre-selection is of no importance to the present invention.

A calling subscriber, on lifting his receiver, is automatically connected in any known manner, for instance, by means of first and second pre-selectors with a line leading to a connector or, if the exchange has more than 10,000 subscribers, to a group-selector serving to select the 10,000 group in which the required subscriber's line is to be found. In the following it is assumed that the connections are established over such group-selectors. In connection with each selector is arranged a connector finder operating to extend the connection to an idle connector of the 10,000 group in question.

Each operator's position has allotted to it a certain number of junctions j leading from the second pre-selectors to the group-selectors GS. Said junctions are divided into two main-groups or sections PS_1 and PS_2 , each comprising two sub-groups SG_1 and SG_2 . Only one junction a, b, c is shown fully connected up to the operator's position.

Each operator is provided with a key-board

KB, associated with an impulse transmitter IT, Fig. 2. Allotted to each sub-group SG is a register or call storing device CS, Fig. 2, which by means of a relay RR_1 or RR_2 , can be connected to the key-board and its impulse transmitter. Only one register, viz. that one belonging to the sub-group SG_2 of the section PS_2 , is shown in the drawing.

The register CS consists of 5 register switches corresponding to the different digits of the subscriber's numbers and operated by electromagnets RE_1, RE_2, RE_3, RE_4 and RE_5 . The operation of the register is controlled by an auxiliary switch or register controller O having a number of sets of contacts arranged in four contact positions and four sections I, II, III and IV. The contacts of each sections are operated by a separate switch arm and all switch arms are mounted on the same shaft carrying a ratchet wheel operated by an electromagnet OE. The various sets of contacts will be referred to in the following description by designations 1:2 (i. e. the second of the first section) IV:4 (i. e. the fourth set of the fourth section) and so on. For the purpose of controlling the connecting operations the register is connected with the calling junction by means of relays R_1 and R_2 , Fig. 2, over a corresponding set of bus-bars $S_1—S_8$, Fig. 1.

Each group-selector GS has associated with it a number of connector finders CF (three being shown) the contact arms of which are mounted on the same shaft. The number of connector finders corresponding to the number of 10,000 groups.

The impulse sending device by which the control impulses are sent from the connector to the register, comprises contact ribs a, b , Fig. 3, a number of series of contact strips and sliding contacts S_1, S_2 movable with the contact carrier of the connector. For the sake of space the ribs a and b and the contact strips are drawn in one and the same direction though they must, of course, in the practical arrangement be placed one part horizontally and the other part vertically.

The group-selectors, connector-finders and the connectors are driven by continuously rotating shafts by means of electromagnetic clutches.

When the second preselector has reached the selector-line marked as disengaged a current flow will be obtained through the whole winding of the calling relay of the preselector, through the c -line over the point z_1 , the contact 300 of the cut-off relay UR_1 , through the lamp relay LaR_1 , over the indicating bar m_1 , through the upper winding of the indicating relay MR_1 , the contact 301 on the indicating relay MR_2 , and the contact 302 in the operator's microtelephone-jack and to earth. The contact 302 is closed, when the operator has his microtelephone

switched in, but is opened when the micro-telephone is taken away and thus the operator's position is marked engaged.

As the resistance of the above-described circuit up to the bar m_1 is very small, while MR_1 has a comparatively great resistance, the bar m_1 will obtain such a potential, that no other 2nd speech selector, testing the c -line belonging to the operator's position can 10 be connected to said position. All c -lines connected to m_1 will be marked engaged as long as the described condition remains. When MR_1 is excited, its contact 303 is closed and accordingly the bars m_1 and m_2 15 connected, whereby all the c -lines, connected to both said bars, will be marked engaged. Thus only one call can come in at one time on this half of the key-board, but another call may be received on the second half by 20 closing of the circuit from the c -line of a 2nd preselector over m_3 or m_4 and through M_2R_1 over a contact in an indicating relay corresponding to MR_2 and to earth.

When MR_1 is excited, its contact 304 is 25 also closed, whereby current is obtained over the contact 305 on the operating relay ER_2 , and through the operating relay ER_1 . Hereby ER_1 is excited and its contacts 306 and 307 are opened and the contacts 308—310 30 are closed. On account of the disconnection at 306, ER is prevented from being energized and by the closing of 308 and 309 the operator's telephone set is connected over the condensers K_3 and K_4 with the line bars t_1 35 and t_2 . When LaR_1 was excited and its contact 311 closed, current was obtained from the battery through the lamp La_1 , 311, the bar ls and the contact 307 to earth, which makes the lamp La_1 light. When now 40 307 is opened, the lamp La_1 will lose its constant current, but will instead of that obtain intermittent currents over the contact 310 and the interrupter I_4 and thus the lamp will burn with a flashing light. When LaR_1 45 was excited, its contacts 312 and 313 were also closed, whereby the a - and b -lines from the second preselector are connected with the line bars t_1 and t_2 and as these as before mentioned, are connected with the operator's telephone apparatus by relay ER_1 , the calling subscriber will obtain speech connection with the operator and can demand the desired number. The operator marks the desired number on the key-board and then 50 presses the starting button SK_1 that is just opposite the flashing lamp, that is the lamp corresponding to the connection just switched in to the operator. When LaR_1 was excited, its contact 314 was excited, 55 whereby current was obtained from earth over 314, the bar r_1 , the register relay RR_1 and to the battery. RR_1 is thus excited and all its contacts are closed. When now the starting button SK_1 is pressed down, its 60 contact 315 is at first closed, whereby the

current coming in from the second preselector over the c -line, is transmitted over 315 and through UR_1 to earth. UR_1 is thus excited and its contact 300 is opened and 316 closed. By the closing of 316, UR_1 will obtain holding current over the contact z_1 , so 70 that UR_1 will remain excited (in spite of the disconnection at 315, when SK_1 is released) until disconnection takes place after the end of the conversation. UR_1 has a so great resistance that the calling relay of the second preselector will remain excited and the connection taken by the preselector will still be marked engaged. By the disconnection at 75 316 the current through LaR_1 and MR_1 ceases and these relays will be released. Thereby the talking connection between the calling subscriber and the operator is naturally broken, the lamp La_1 is cut off, the connection between the bars m_1 and m_2 is 80 opened and the operating relay ER_1 will be without current. When ER_1 is released and its contact 306 is closed, ER_2 for the second half of the position will be free to be operated and if a call has arrived on this part 85 of the key-board, the subscriber will now by influence of ER_2 be connected with the operator's telephone. When the button SK_1 was pressed down, its contact 317 was also closed, whereby the following circuit is obtained: 90 earth, 317, the bar s_1 , and through the motor M of the impulse machine to the battery. Over the same current contact is also obtained over the contact 318 through RR_1 to the battery. As before mentioned, RR_1 95 was excited when 314 of LaR_1 was closed and thus RR_1 will remain excited in spite of the opening of 314 at the same moment when CK_1 is pressed down. When the motor begins to rotate, the contact 319 is closed, 100 whereby the motor as well as RR_1 are grounded and will then accordingly remain excited (in spite of the disconnection at 317 when SK_1 is released) until 319 again is opened when the impulse machine has 105 rotated one revolution. When the impulse machine begins to rotate, a number of current impulses are obtained through the registers RE_1 — RE_5 respectively, which impulses correspond to the keys depressed in the switch- 110 board.

The registers are connected through their respective contacts on RR_1 each with one ring on the impulse machine and as the buttons in the different rows of the key-board 115 will ground the same number of contact blades in the respective sections of the impulse machine as corresponds to the number of the pressed buttons, the registers will obtain the same number of impulses and thus 120 take up positions corresponding to the buttons pressed down. As the contact 320 of RE_5 was closed at the same moment RE_5 left its initial position the indicating relay MR_2 was excited in the same moment where- 125 130

by its contact 301 was opened and 321 was closed. By this latter connection the lamp La_2 will begin to glow and continues to do so until MR_2 will be currentless, that is until 5 RE_5 returns to its initial position. By the disconnection at 301, the earth connection for the upper winding of M_1 R_1 is broken, which effects that no further subscriber can reach the corresponding part of the right 10 half of the operating board before RE_5 has again reached its normal position, that is before the set of register switches taken in use is again entirely disconnected. If a second preselector when seeking a disengaged 15 connection to a selector passes over the c -lines coming in to the bar m_1 , its calling relay cannot be excited, so long as the disconnection at 301 remains. Thus it has been shown, that a call can simultaneously come 20 in on each of the halves on the key-board, but that only one of these at a time may be switched in to the operator's telephone and besides, that when the operator has executed an order for a conversation, no further call 25 can reach the quarter of the operating table, that corresponds to the lastly executed call until the connection is complete. The second quarter of the same half of the position is however marked disengaged at the same moment when a starting button belonging to 30 this second half is pressed. If a call came in for example on some one of the cords belonging to the bar m_2 while connecting operation takes place on some one of the 35 cords belonging to the bar m_1 , that is if the operator has pressed the corresponding starting button, but the registers are still working, then besides a lamp relay corresponding to LaR_1 also MR_1 will be excited on account 40 of the current through its lower winding. Thereby the relays RR_2 and M_1R_2 will apparently be brought in action in the same manner as RR_1 and MR_2 and by influence of RR_2 , the impulse machine is switched in to a 45 second set of register switches.

At the same moment the starting button was pressed down, besides 315 and 317, 322 was closed, whereby the following circuit was obtained: earth, 322 and the relays R_1 , 50 and R_2 to the battery. When R_1 is excited its contact 323 is closed, whereby the two relays will receive holding current over 323, the bar s_7 , and 320 of RE_5 . R_1 and R_2 thus remain excited until the connecting operation 55 is entirely finished. By the disconnections at 324 and 325 of R_1 the calling subscriber is cut off and by the closing of 326 and 327 the a - and b - lines in the selector are connected over the bars s_2 and s_3 , respectively with the line relays LR_3 and LR_4 (over 166 of the relay V). By the closing 60 of 328 of R_1 , the d -line of the selector is over s_4 connected with the lowest spring of the relay V . By the closing of the contact 329 65 of R_2 connection will be obtained from the

clutch electromagnet MK_3 to the bar s_5 and further over the contact 25 of the register switch RE_1 to the battery, and the selector will thus be made to rotate at the same moment R_2 is excited. By closing the contact 70 330 of R_2 connection will be obtained from the contact 152 of the calling relay LyR_3 over the bar s_6 to the contact 26 of RE_1 .

In this specification the contacts specially adapted for the semi-automatic arrangement have been indexed with numbers from 300 and upward, while lower numbers have reference to the preceding description of the full automatic system. As the restoring of the register switches and so on, after they 75 have been adjusted by means of the keyboards takes place in accordance with the same principles as in the full automatic system it has not been considered necessary to here describe these details. Reference is 80 made therefore in applicable parts to the description of the full automatical system. Below will be given only a short account of the succeeding operations. When the impulse machine started to rotate its contact 85 332 was closed, whereby current was obtained through the operating electromagnet OE of the switch O and when 332 is opened after the register switches have been set and the impulse machine has returned to its 90 initial position, the auxiliary switch will accordingly reach its second position. Through the contact $IV:2$, earth connection is obtained over the contact 25 of RE_1 , the bar s_5 , 329 of R_2 and through the magnetic 100 clutch MK_3 , and the selector will therefore as indicated above start to rotate. In the usual way impulses from the selector are thereby obtained and these are transmitted over $I:2$ through the register RE_1 , that is 105 moved step by step, until 25 is opened when the movement of the selector ceases. By closing the contact 26 the relay R_3 in the selector will now be excited in the same way as at the full automatic system, thereby making the connector-finder rotate which continues until a free connector has been found, when LyR_3 is excited and the contact taken 110 is marked engaged.

When R_3 was excited the following circuit was obtained: earth, 157, 231, s_8 , and through OE to the battery, and when the current through R_3 ceases at the same moment the disengaged connector is found, the current through OE will thus be broken 115 and the reverser reaches its third position. The connector now begins to move in the same way as before described for the full automatic system either to the right or to the left, depending upon the position taken 120 up by RE_2 , that is depending upon whether only O_2E_2 or both O_2E_2 and V have been excited. As will be seen, V is over $III:3$ connected with the contact 32, and O_2E_2 is over $III:3$ (the outer contact) connected 125 130

with 33. During the movement of the connector, the impulses on the *a*-, *b*-, and the *d*-lines will excite RE_2 and RE_3 and when these two have returned to the normal position, the horizontal motion of the connector will cease. As O_2E_2 in the same moment will be deprived of current, its contact 173 is opened, whereby OE , which during the horizontal motion has been energized, now will be currentless and the auxiliary switch will reach its fourth position. After this the connector begins its vertical motion and continues same until RE_5 has returned to the normal position, when the auxiliary switch again reaches its initial position on account of the disconnection at 173 of O_2E_2 . When 320 of RE_5 is opened, the current through MR_2 ceases, which has the effect that the lamp La_2 is extinguished and the upper winding of M_1R_1 is grounded. The corresponding quarter of the operator's position, hitherto marked engaged will thereby be made free for a new call from another 2:nd preselector.

25 Besides this, a disconnection of the current through R_1 and R_2 will be obtained by the opening of 320 of RE_5 , and as the relays R_1 and R_2 now are released, the calling subscriber will be connected over the selector and so on. Already at the same moment when the calling subscriber was connected with a selector, the clearing-signal relay AR_2 was switched in to the *a*- and *b*-branches and the calling subscriber will during the whole time obtain his current feed through this relay.

With the selector is associated a special one-armed auxiliary switch O_1 which is mechanically connected with the switch O in such manner that it follows the latter step by step until and including the fourth step but which has no electrical function until it reaches the fifth position when it switches in the back-relay BR to the *d*-line. 45 (This auxiliary switch reaches its fifth position at the same moment when the other returns to its first position.) When the subscribers hang up BR will in the same way as in the full automatic system be energized and its contact 198 will be closed, whereby follows that OE_1 receives a current, that ceases at the same moment when BR is currentless after the connector has been restored to normal position.

55 When thus the auxiliary switch is thereby moved into its first position, MK_3 and MK_4 will obtain current over the contacts 93 and 94 respectively, and thus the selector and the connector-finder will be brought back to the initial position.

As the selector is now entirely restored to the normal position and as the battery connector, to the *c*-line over the contact 96 of AR_2 of the selector and 97 of the connector finder is broken, the selector after

this is obviously ready for a new call. When said battery-connection on the *c*-line ceases, UR_1 will be released and LaR_1 will again be switched in to the *c*-line for the receiving of a new call.

70

The mechanical operating of the connector.

The connector is movably arranged upon a carriage, movable horizontally upon one or more beams, which again are vertically movable on vertical beams.

75

The clutch electromagnets M_1K_1 , M_1K_2 and M_2K_2 are so arranged, that when they are excited they fix clutch rope pulleys or similar arrangements which normally can move freely on their shafts, to the said shafts. These rope pulleys pull said carriage by means of an endless wire in one or the other horizontal or vertical directions according as one or the other clutch electromagnet is energized.

80

The brakes MB_1 and MB_2 , which are operated when the clutch electromagnets are disconnected, only serve the purpose of securing an instantaneous arresting of the carriage or the connector. The mechanical features of the connector are described more in detail in the above-mentioned application #841,966.

90

I claim—

95

1. A semi-automatic telephone exchange system comprising an operator's position, a group of junctions associated therewith and divided into a number of sub-groups, call storing devices associated one with each sub-group and means for making all junctions of the group inaccessible for further calls when a call is made on one of them.

100

2. A semi-automatic telephone exchange system comprising an operator's position, a group of junctions associated therewith and divided into a number of sub-groups, call storing devices associated one with each sub-group, means for engaging all junctions when a call is made on one of them and means for disengaging a number of junctions as soon as the call has been attended to by the operator.

105

3. A semi-automatic telephone exchange system comprising an operator's position, a group of junctions associated therewith and divided into a number of sub-groups, call storing devices associated one with each sub-group, means for engaging all junctions of the group when a call is made on one of them, means for disengaging all junctions except those of the calling sub-group as soon as the call has been attended to by the operator and means for disengaging the junctions of the calling sub-group when the connection is completed.

115

4. A semi-automatic telephone exchange system comprising an operator's position, a group of junctions associated therewith and divided into a number of sub-groups, call

120

125

130

storing devices associated one with each sub-group, means for engaging all junctions of a sub-group when a call is made on one of them and means for engaging all junctions associated with the operator's position when a certain maximum number of unattended calls are received at the operator's position.

5. A semi-automatic telephone exchange system comprising an operator's position, a group of junctions associated therewith and divided into a number of sub-groups, call storing devices associated one with each sub-group, means for engaging all junctions of a sub-group when a call is made on one of them, means for engaging all junctions associated with the operator's position when a certain maximum number of unattended calls are received at the operator's position and means for disengaging a number of junctions as soon as one call has been attended to by the operator.

10. 6. A semi-automatic telephone exchange system comprising an operator's position, a

number of junctions associated therewith and divided into a number of main groups 25 each main group being divided into a number of sub-groups, call storing devices associated one with each sub-group and means for allowing only one unattended call to be received at any one time in each main group. 30

7. A semi-automatic telephone exchange system comprising an operator's position, a number of junctions associated therewith and divided into two main groups each main group being divided into two sub-groups, a call storing device particularly associated with each sub-group and means for allowing only one unattended call to be received at any one time in each main group. 35

In testimony whereof I affix my signature 40 in presence of two witnesses.
